UNITED STATES PATENT OFFICE.

CARREL FISHER, OF PASCOLA, MISSOURI.

QUICK-RELEASING CONNECTER FOR COTTON-BALE BANDS.

Application filed August 30, 1923. Serial No. 660,201.

To all whom it may concern:

Be it known that CARREL FISHER, a citizen of the United States, residing at Pascola, in the county of Pemiscot and State 5 of Missouri, has invented new and useful Improvements in Quick-Releasing Connecters for Cotton-Bale Bands, of which the following is a specification.

The present invention has for its purpose 10 to provide, in a quick releasing connecter for cotton bale bands, a construction which includes a body connected at one end to one end of the band, in conjunction with a lever operatively mounted in the body and connected 15 to the other end of the band whereby, upon exerting a pull between the lever and the body, the lever may be moved toward the bale whereby a tongue of the lever may be quickly detached from a loop and thereby 20 release the band.

Another purpose is to provide a connecter including a slide for holding the lever in such position as to prevent detachment of the loop from the lever.

25 The invention comprises further features and combinations of parts to be hereinafter set forth, shown in the drawings and claimed.

In the drawings:

30 Figure 1 is a view in perspective of a bale of cotton showing binding bands passing about the bale at right angles to each other and showing the connecter applied.

Figure 2 is a sectional view on line 2—2 35 of Figure 1, taken longitudinally through the connecter.

Figure 3 is a sectional view similar to Figure 2 but showing the connecter inverted to that in Figure 2 whereby the lever 12 40 may be moved outwardly from the bale for disconnecting the lug 16 from the loop 17.

Figure 4 is a detail perspective view of the body of the connecter looking under the same, showing the lever in a tilted position 45 whereby a loop connected to one end of the band may be released.

Figure 5 is a cross sectional view on line 5—5 of Figure 4.

Referring to the drawings, 1 designates 50 the body of the connecter which may be constructed of any suitable metal, either sheet or cast. The body is of elongated form, U-shaped in cross section, and one end thereof is provided with extensions 3 having lateral arms 4 extending toward each other. The arms 4 are spaced from the end edge of the

top wall of the body, thereby causing to be formed a transverse slot 5. The arms 4 have their adjacent ends spaced, as shown at 6, whereby a looped end 7 of a cotton bale 60 band 8 may be inserted. In fact, the looped end of the band is first angularly disposed, allowing the band to pass between the spaced ends of the arms 4 so that the fold of the loop may assume a position in the 65 slot.

The other end of the body is provided with extensions 9 constituting ears for the reception of a pivot bolt or headed pin 10 on which the ears 11 of a lever 12 are pivotally mounted. The body portion of the lever, when the connecter is in operative position, lies against the under face of the top of the body. The opposite flanges or sides of the body are provided with registering elongated slots disposed on slight angles to the top of the body. In other words, the slots 13 are inclined in a direction from the pivot of the lever slightly toward the bale, and mounted in the slots is a slide 14 which 75 extends transversely of the body. The ends 15 of the slide are upturned to retain the slide in the slots and to prevent transverse movement thereof. However, the slide is capable of movement in the slots and when 80 the lever is engaged with the under face of the top of the body of the connecter, the slide assumes a position transversely of the end of the lever to prevent the lever from being tilted in a direction toward the bale. 85 The slide is held frictionally in position due to its contact with the walls of the slots.

The pivoted end of the lever has an extension lug 16 which is disposed in a direction toward the bale slightly inclined toward the pivot of the lever. This lug 90 engages with a metal loop 17 which has arms 18 similar to the arms 4. The other end of the cotton bale band has its looped end 19 engaged with the arms of the metal 100 loop 17, thereby connecting the two ends of the band. The looped end 19 of the band may be connected with the arms of the metal loop in the same manner as the other looped end of the band connects with the 105 arms 4.

In order to release the band, an instrument may be inserted between the top of the body and the lever, after the slide has been moved in order to release the free end 110 of the lever, and by applying pressure on the lever, forcing it in the direction of the

bale, and at the same time prying the body outwardly, the lug of the lever will move, whereby it may disengage from the loop and hence release the cotton bale band.

5 It will be noted in Figure 1 that two of the bale bands are applied with the connectors reversely disposed. In fact, one of the connectors is disposed with the edges of the flanges of the body of the connector in 10 contact with the bale while the other is disposed with the edges of the flanges facing outwardly. This arrangement illustrates the fact that the connector can be disposed either way. With the connector disposed so 15 that the edges of the flanges of the body of the connector are adjacent the bale, it is necessary to move the lever 12 toward the bale by inserting an instrument between the body of the connector and the lever in order 20 to disconnect the lug 16 from the metal loop 17. When it is desired to detach the band from the connector which has the edges of its side flanges facing outwardly, it is necessary to pry the lever 12 in a direction 25 away from the bale, as shown in Figure 3, to cause the lug 16 to disengage from the loop 17.

Having set forth the invention, what is claimed is:

30 1. In combination with a cotton bale band having looped ends, of a connector including a body having a slot at one end for the reception of one of the looped ends, a lever

pivoted in the opposite end of the body, means carried by the other looped end and 35 operatively connected with the pivoted end of the lever whereby the lever may quickly release said means when the lever is moved pivotally in a direction toward the bale, and means carried by the body and lying trans- 40 versely of the end of the lever to retain it against the under surface of the top wall of the body to maintain a connection between said band connecting means and the lever. 45

2. In combination with a cotton bale band having looped ends, of a connector including a body having a slot at one end for the reception of one of the looped ends, a lever 50 pivoted in the opposite end of the body, means carried by the other looped end and operatively connected with the pivoted end of the lever whereby the lever may quickly release said means when the lever is moved pivotally in a direction toward the bale, means carried by the body and lying trans- 55 versely of the end of the lever to retain it against the under surface of the top wall of the body to maintain a connection between said band connecting means and the lever, said last mentioned lever retaining means comprising opposed inclined slots formed in the sides of the body, and a slide engaged in said slots to overlie the lever. 60

In testimony whereof he affixes his signature.

CARREL FISHER,
